SUCTION CLEANER

Uncas A. Whitaker, Canton, Ohio, assignor to The Hoover Company, North Canton, Ohio, a corporation of Ohio

Application January 2, 1935, Serial No. 113

1 Claim. (Cl. 21—127)

The present invention relates to suction cleaners in general and particularly to an odorizer unit in a suction cleaner construction. More specifically the invention comprises new and novel features in an odorizer unit which is adapted to form a part of a suction cleaner unit.

It is an object of the present invention to provide a new and improved odor-creating means in a suction cleaner. Another object of the invention is to provide, in a suction cleaner unit, an odorizer unit having available a plurality of odor-creating volatile agents and which is provided with selective means by which the operator can control the odor produced. Still another object of the invention is to provide a novel odorizer unit including a plurality of scent-producing elements. A still further object is to provide, in a suction cleaner unit, an odorizer unit in which a moving air stream, drawn by the suction-creating means, passes selectively over one of a plurality of volatile agents. A further object is the provision of an odorizer unit for a suction cleaner which includes manually operable valves to enable the operator to control selectively the scent produced by the unit in operation. Still another object is the provision of an odorizer unit in which the passage of an air stream therethrough is controlled by a manually operable valve which directs the air stream over one of a plurality of odor-producing volatile agents included in the construction. Still another object of the invention is the provision of an odorizer unit which is embodied as an attachment element adapted to be connected to the end of the dusting tool hose carried by the cleaner and which is provided with a manually operable valve to control the flow of air past the volatile agent. These and other more specific objects will appear upon reading the following specification and claims and upon considering in connection therewith the attached drawings to which they relate.

Referring now to the drawings in which preferred embodiments of the present invention are disclosed:

Figure 1 is a side elevation of the suction cleaner embodying the first preferred embodiment of the invention;

Figure 2 is a side elevation of the removable part of the air passageway between the nozzle and the fan chamber upon which the odorizer unit constructed is embodied;

Figure 3 is a view of the construction shown in Figure 2 at right angles to the showing thereof;

Figure 4 is an enlarged view of the manually operable control for the unit valve;

Figure 5 is a view in perspective of one of the agent receptacles removed from the unit;

Figure 6 is a cross section upon the line 6—6 of Figure 2;

Figure 7 is a vertical section upon the line 7—7 of Figure 3;

Figure 8 is a section through the receptacle seats upon the line 8—8 of Figure 6;

Figure 9 is a section through the valve chamber upon the line 9—9 of Figure 6;

Figure 10 is a showing of a second preferred embodiment of the invention included in a suction cleaner assembly, the suction cleaner unit proper being shown in side elevation;

Figure 11 is a section through the odorizer unit illustrating its connection with the end of the dusting tool hose, being taken upon the line 11—11 of Figure 12;

Figure 12 is a top plan view of the structure shown in Figure 11;

Figure 13 is a transverse cross section through the unit upon the line 13—13 of Figure 11.

Figure 14 is a transverse cross section upon the line 14—14 of Figure 11.

In the operation of a suction cleaner in the home the air which passes through the cleaner is observed, by persons with sensitive olfactory senses, to be characterized by a "dry" scent or odor. To disguise this slightly disagreeable effect the modern suction cleaner is provided with an odorizer unit which gives off a pleasant odor which serves to disguise the natural smell of the air and to render it pleasant. The use of a cleaner in a room with the odorizer in operation results in the scenting of the air in the room with the scent of the volatile agent used in the unit.

The various rooms of a home have their own characteristics and a particular housekeeper often desires to maintain the personality of each room intact. To assist in this the suction cleaner embodying the present invention is provided with a plurality of odor-producing agents which are controlled by the operator so that the odor produced in a room is determined by the operator. According to the present invention, this result is accomplished in an efficient and novel manner as hereinafter fully disclosed.

Referring now to Figures 1 to 9, inclusive, the first preferred embodiment of the invention is disclosed. In Figure 1, in particular, a modern suction cleaner is shown. The cleaner nozzle 1 is connected to the fan chamber 2 through an air passageway 3, the part thereof immediately adjacent the fan chamber 2 being formed as a removable element in a manner well known in

10

20

the art. This element is known as the pulley housing cover, or merely as the removable part of the air passageway. The fan chamber is provided with an exhaust outlet 4 to which is attached a dust bag 5 which functions in the operation of the machine to filter from the air passing therethrough the suspended foreign matter which has been collected from the surface covering undergoing cleaning. A motor casing 6 is positioned above the fan chamber 2 and encloses an unshown driving motor of the usual sort which drives the suction-creating fan 7 positioned within the fan chamber 2. The cleaner is supported upon front and rear wheels 8 and 9 and a pivoted handle 10 is provided by which the operator can exert the necessary force to propel the machine in its operation.

The odorizer unit constructed in accordance with this embodiment of the invention, is a part 20 of the removable casing 3 and as such is adapted to be sold therewith as a unit to be embodied in cleaners unprovided with an odorizer unit. For this purpose, the member 3 is of the usual 25 and well known type, being provided with forwardly-projecting lugs, one of which is indicated by the reference character 11 in Figure 2, and by a rearwardly projecting shoulder 12. Each lug 11 is adapted to seat within a suitable recess in the nozzle 1 while the shoulder 12 is adapted to be 30 secured on the underside of the fan chamber 2 by the manually operable latch means 13. This type of construction is well known in the art as is evidenced by the patent to H. C. Hettelsater, 1,575,363. The removable cover 3 includes a casting 35 15 which is formed interiorly with a cylindrical body cavity open at one end and normally closed by a pivoted cover plate 16 which is held in place by a manually operable leaf spring detent 17. In the casing 15 is provided a hollow 40 cylindrical member 18 entirely open at one end and formed with a closing wall at its inner end. Member 18 is formed as, and is divided into, a plurality of similar seats by a centrally positioned longitudinally bored tube 19 and by radially extending walls 20, 20, 20. A separate receptacle 45 seat is formed between each pair of walls, and each seat is connected to the body cavity forward of the seat by a pair of radially spaced ports 21 and 22.

Forward of the receptacle seats the cavity of housing 15 is formed as a valve chamber which 50 is divided into an inner chamber 23 and an outer chamber 24 by a circular wall 25. The centrally bored tube 19 connects the inner chamber 23 to the exterior atmosphere through being open at its outer end to the atmosphere through ports formed in the pivoted cap 16. The wall 25 between the chambers 23 and 24 is of such radius 55 that it is positioned radially between, though spaced axially from, the ports 21 and 22 in the individual receptacle seats. The outer chamber 24 of the valve chamber is connected by a passageway 26 to the interior of the casing member 3 so that, with the cleaner in operation, air will be drawn from the exterior atmosphere, through the tubular member 19 into the valve chamber 23, and through the passageway 26 into the eye 60 of the fan chamber.

To control the flow of air through the odorizer unit and to cause it to accomplish a useful purpose there is provided a rotatable valve element 70 75 which rotates about the extended end of the tube 19 as an axis and is positioned between the circular wall 25 and the adjacent inner face

of the member 18. Valve 27 is formed with radially extending ports 28, 28 etc. which are adapted to overlie selectively any pair of ports 21, 22 opening into a particular receptacle seat, or to be so positioned that they fail to mate with all 5 of the ports 21 and 22. With the valve element 27 so rotated that a particular port 28 coincides with a particular pair of ports 21 and 22 the air in passing through the unit and from the inner valve chamber 23 to the outer valve chamber 24 will, of necessity in order to get past the circular wall 25, travel through the port 28, through the port 21 into the receptacle seat and from that seat through the port 22 and again through the port 28 to enter the outer valve 10 chamber from whence it will be drawn via the air passageway 26 into the fan chamber. Slight leakage will occur immediately between the wall 25 and the adjacent face of the receptacle seat but the air leakage is relatively insignificant as 15 compared to the air which will pass through receptacle seat opened by the valve port.

The position of the valve 27 is controlled by a manually rotatable element 29 which is carried at the end of a rotatable shaft 30 mounted in a 25 laterally extending shoulder on the casing 15. The inner end of shaft 30 is rigidly connected by an L-shaped member 31 to the valve element 27. Any rotation of the element 29 results directly in the rotation of the plate valve 27, unintended movement being prevented by a coil spring 32 which seats within a counter-bored seat surrounding the shaft at the end of the shoulder and which acts against the inner end of the knob 29. Cooperating indicating means upon the knob 35 30 29 and upon the shoulder adjacent thereto, comprising an arrow which is adapted to extend adjacent markings upon the knob 29, evidence the valve position.

The volatile odorizing agent for use in the present invention is carried by a receptacle 35, which 40 conforms in shape to the individual seats in the member 18. A receptacle is adapted to be positioned in a seat through being forced thereinto from the open end when the cover 16 is pivoted to 45 its open position. Once within its seat it is held therein by a spring 36 carried by the cap 16. The volatile element may be of any preferred type such as a cake, or maybe a body of wick material saturated with a volatile redolent agent. The 50 volatile element preferably does not extend entirely to the open end of its receptacle but is spaced slightly therefrom, as is clearly indicated in Figure 5, making it possible for a stream of air to pass into and through the end of the receptacle with the valve 27 so positioned as to direct air into the seat in which it is positioned.

In the operation of this preferred form of the invention the placing of the cleaner in use causes air to be drawn from the nozzle 1 and exhausted 60 into the dust bag 5. The operator upon determining that a certain odor is desired in the room in which the cleaning is being done moves the manually operable knob 29 from the "off" position to one of the positions in which the arrow 65 points to one of the numerals carried by the knob. Each numeral indicates a particular valve position and so a particular scent, and by knowing the relationship of the scents to the numerals, the operator can determine the correct position 70 of the knob. With the knob positioned so that one of its numerals is opposite the indicating arrow the valve is so positioned that the air drawn through the odorizer unit passes into the receptacle containing the volatile agent which creates 75

the desired scent. The air enters the receptacle, passes over the surface of the agent and leaves the receptacle to pass through the outer valve chamber 24 and into the air passageway 3, the point of low pressure, via the passageway 26. At the conclusion of the cleaning operation it is preferred that the manually operable knob 29 be moved to the "off" position in order to prevent unintended and unnecessary volatilization of the agents.

Referring now to Figures 10 to 14 inclusive, in particular, a second preferred embodiment of the invention is disclosed. According to this embodiment the suction cleaner is constructed as in the first embodiment with the exception that the removable air passageway member 3 is of the usual well known type and does not include the odorizer unit. The dust bag 5 of the cleaner has been removed and to the exhaust outlet 4 has been attached a blower connection 40 to which is secured an elongated flexible hose 41, commonly known as the dusting tool hose. The outer end of the dusting tool hose is formed with a metallic seat member 42, which is shaped at its extreme outer end, as a channel. Seat member 42 is adapted to receive and seat any one of a plurality of dusting tool cleaning elements. According to the present invention the odorizer unit element is connected to the end of the hose 41 and specifically to the seat 42 thereof.

The unit comprises a hollow cylindrical metallic body 43 which is slightly flared at its outer end and which is of such size at its inner end that it is adapted to closely enclose and seat upon the metallic seat of the hose 41. The spring-pressed 35 detent 44, of a common and well known type, extends through the body 43 and seats within the channel at the outer end of member 42 and functions to prevent the unintentional separation of 40 the member and of the hose. Rearward of the detent 44 the body 43 is enlarged and there is positioned therein a cylindrical mounting member 45 which is mounted on the body 43 by screws, indicated by the reference character 46. The 45 outer end of support 45 is open, while the inner end is formed with a reduced collared opening 47. Within the support 45 and spaced therefrom at all except the supporting points is a second cylindrical member 48. Screws 48, 49, 49 support the member 48 in the support 45 so that it extends 50 rearwardly to the end of the member 45 while its forward closed end is somewhat short of the collared opening 47. Member 48 is divided by radially extending walls 50, 50, 50 into three seats, 55 each of which is adapted to receive an agent-containing receptacle. Each receptacle seat is provided at its forward end with a port, only one in the present case, indicated by the reference character 51. The agent receptacle or container is indicated by the reference character 52, being 60 of the same type as in the first embodiment, and when in place within a seat is held against outward displacement by spring arms 53 carried by a pivoted closure member 54 which is itself held in position by a manually operable leaf spring 65 detent 55.

The valve member of the present embodiment, which is indicated by the reference character 56, includes a cylindrical portion 57 and is rotatably positioned at the side of the closing wall of seat member 48. A hollow lug at the center of the valve element extends through an opening in the

wall where it is expanded and serves to hold the valve to the wall while permitting it to rotate. The valve is also mounted in the collared opening 47 as a bearing through its cylindrical portion 57 seating therein. As in the first embodiment the valve includes circumferentially spaced ports, indicated by the reference characters 58, and with a port 58 adjacent and opposite to a port 51 the interior of the receptacle seat, and so the receptacle, is open to the interior of the body 43 and so to the interior of the dusting tool hose 41.

The position of valve 56 is controlled by a radially extending lever arm 59 which is non-rotatably secured relative to the cylindrical portion 51 of the valve by a lock nut 60. The outer end of the lever passes through the body 43 in a slot 61 which is divided into spaces by markers and at certain spaces are provided numerals to indicate a valve position. Opposite a certain space is found the word "off" indicating that with the lever arm positioned in that position the valve has been moved to the off position. Unnecessary and undesired leakage of air through the slot 61 is prevented by a seal plate 62 which is carried by the lever 59, which, through conforming to the curvature of body 43 and being of sufficient length at all times closes the slot.

In the use of the present invention the suction cleaner is connected as indicated in Figure 10, the dust bag being removed and the dusting tool hose being connected to the exhaust outlet of the machine. In this relationship air is blown through the machine and through the odorizer unit connected at the end of the dusting tool hose. With the control lever 59 positioned to the "off" position, no air passes through the unit in the sense of passing over a volatile agent. With the lever positioned in either of its three working positions the unit is operative. The air enters at high velocity having been exhausted under pressure from the hose 41 and is forced through the cylindrical part of the valve 51, through the mouth of the receptacle and down the passageway formed between the cylindrical member 48 and the support 45 to join again the main body of the air stream at the flanged opening of the body 43. If a different odor is desired the operator need only change the lever 59 from one position to a second, as in the first embodiment. With the valve in the "off" position all of the air passing through the body 43 passes around and at the sides of the cylindrical mounting member 45.

I claim:

In an odorizer unit, a body formed with an open ended cavity and with a passageway extending from the inner end of said cavity adapted to be connected to a source of suction, a plurality of seats in said cavity adapted to receive volatile-element-containing receptacles, receptacles adapted to contain differently scented volatile elements positioned in said seats, the inner end of said cavity forward of said receptacles being formed as a valve chamber open to said passageway, a second passageway connecting said chamber to atmosphere, valve means in said chamber adapted to connect selectively any one of said receptacles between said passageways so that air passing therebetween passes into contact with a volatile element, and control means operable from the exterior of said body to control manually the position of said valve. 55 60 65 70
